UNITED STATES PATENT OFFICE.

LABAN H. CULBERTSON AND WILLIAM KIRKPATRICK, OF DEXTER,
MISSOURI.

BALING-PRESS.

SPECIFICATION forming part of Letters Patent No. 681,200, dated August 27, 1901.

Application filed March 27, 1901. Serial No. 53,111. (No model.)

To all whom it may concern:

Be it known that we, LABAN H. CULBERTSON and WILLIAM KIRKPATRICK, citizens of the United States, residing at Dexter, in the county of Stoddard and State of Missouri, have invented a new and useful Baling-Press, of which the following is a specification.

This invention relates to baling-presses, and has for its object to provide improvements in the manner of mounting and operating the plunger-rod thereof, so as to obtain an effective operation of the machine and to conveniently take up the jar caused by the rebounding of the plunger. It is furthermore designed to insure a steady and continuous forward movement of the plunger and to arrange for tripping the operating mechanism at the proper instant to permit of the rebounding of the plunger out of the way of the feeding device, which is thrown into operation immediately after the rebounding of the plunger.

With these and other objects in view the present invention consists in the combination and arrangement of parts, as will be herein-after more fully described, shown in the accompanying drawings, and particularly pointed out in the appended claim, it being understood that changes in the form, proportion, size, and minor details may be made within the scope of the claim without departing from the spirit or sacrificing any of the advantages of the invention.

In the drawings, Figure 1 is a central longitudinal sectional view of a baling-press constructed and arranged in accordance with the present invention. Fig. 2 is a plan section thereof. Fig. 3 is a detail perspective view of the plunger and its plunger-rod.

Like characters of reference designate corresponding parts in all of the figures of the drawings.

Referring to the drawings, 1 designates the frame portion, which supports the operating mechanism, and 2 designates the press-box, which is provided in its top with the usual hopper 3, through which the hay or other material to be baled is fed. Within the baling or press box there is slidably mounted the plunger-head 4, which is slidably in opposite

directions across the floor or bottom of the frame and press-box.

The plunger-rod 5 is in the form of a plate, having one end secured to the middle of the back of the plunger and disposed in a vertical edgewise position, the outer upper corner thereof being rounded and faced with a metallic strap 6 to prevent wear to the wooden plunger-rod. The bottom edge of the rod is slidably supported upon the floor 7 of the frame and is guided between a pair of parallel strips or cleats 8, secured longitudinally upon the top of the floor and embracing the opposite sides of the plunger, the ends of the cleats terminating short of the ends of the plunger-rod. The forward end of the plunger-rod is supported upon a pair of rollers 9, which are mounted upon a suitable spindle 10, projected at opposite sides of the rod, the rollers being disposed outwardly from the respective sides of the rod and mounted to travel upon the floor, so as to reduce the friction as much as possible. In rear of the plunger-rod and aligned longitudinally therewith is a bumper-bar 11, that has its inner end provided with a block of rubber 12 and arranged at the outward limit of the plunger-rod, so as to receive the impact thereof and thereby take up the jar. As an additional means for taking up the jar of the rebound of the plunger there is provided the coiled or helical springs 13, carried by opposite sides of the plunger-rod and connected thereto by means of the brackets 14, the springs being located normally in advance of the forward ends of the guide-cleats and arranged to come in contact therewith at the outer limit of the plunger and thereby take up the jar.

To impart a forward movement to the plunger there is provided a pair of gear-wheels 15, mounted upon a transverse shaft 16, that is carried by the frame 1, the gears being located at opposite sides of and adjacent to the plunger-rod, whereby the latter slides between the wheels. An antifriction-roller 17 is journaled between and carried by the wheels and is arranged to strike the outer end of the plunger, and thereby force the plunger inwardly or forwardly when the wheels are rotated in the direction of the arrow shown 100

in Fig. 1 of the drawings. It will now be understood that the upper rear end of the plunger-rod is rounded to facilitate the engagement of the crank 17 with the plunger-rod.

5 To return the plunger to its original position after it has been forced to its forward limit and the crank has risen out of engagement therewith there is provided a helical spring 18, lying beneath the floor and having 10 its outer end provided with a hook or eye 19 for detachable engagement with an eye or hooked bolt 20 carried by one of the cross-sills of the frame, the opposite end of the spring being connected to the lower end of a 15 bolt or rod 21, that is passed through the plunger-rod and also through a longitudinal slot 22 in the bottom of the floor. It will be understood that said spring is extended during the forward movement of the plunger, 20 and as soon as the operating device is tripped out of engagement with the plunger said spring will contract, and thereby force the plunger rearwardly to its original position, the bumper and the springs 13 taking up the 25 jar of the rebound thereof. Any suitable means may be employed for driving the crank-wheels—as, for instance, a belt-wheel 23, in connection with a suitable engine and mounted upon the frame 1, with intermediate 30 gearing 24 in connection with the crank-wheels.

To pack or feed the material to be baled into the hopper there is provided a lever 25, which is fulcrumed intermediate of its ends 35 upon a suitable bracket 26, carried by the frame of the machine and in advance of the hopper, so that the forward end of the lever may normally lie between the wheels and in the path of the crank 17, just after it disengages from the plunger-rod. A helical spring 40

27 has one end connected to the lever and its opposite end connected to the frame, so as to normally and yieldingly hold the lever in its normal position for engagement by the crank. The opposite end of the lever is disposed centrally over the top of the hopper and is provided with a lateral arm 28, carrying a cross-head or packer 29, which is entered into the hopper, when the adjacent end of the lever is thrown downwardly by the elevation of the 45 opposite end thereof, caused by the crank 17 striking the under side of the lever. After the crank disengages from the lever the spring 27 returns the same to its original position. It will be observed that the operation of the 50 plunger and the packer or feeder is alternate, so that neither interferes with the other.

What is claimed is—

In a baling-press, the combination with the floor of the frame thereof, which is provided 60 with a longitudinal slot, of a plunger, having a plunger-rod slidably mounted upon the floor and over the slot therein, a headed projection carried by the plunger-rod and working in the slot in the floor, the head of the 65 projection lying at the under side of the floor and forming a stop for engagement therewith to prevent upward displacement of the plunger-rod, and a rebounding-spring connected at opposite ends to the headed projection and 70 a part of the frame, the spring also lying below the floor.

In testimony that we claim the foregoing as our own we have hereto affixed our signatures in the presence of two witnesses.

L. H. CULBERTSON.
WM. KIRKPATRICK.
